COLLAPSIBLE, COMBINED VANITY-BENCH MIRROR AND TRAY

Everett O. Ryder, Pleasantville, N. Y.

Application April 7, 1948, Serial No. 145,575

Term of patent 14 years

(Cl. D33—9)

To all whom it may concern:

Be it known that I, Everett O. Ryder, a citizen of the United States, resident of Pleasantville, county of Westchester, State of New York, have invented a new, original, and ornamental Design for a Collapsible, Combined Vanity-Bench Mirror and Tray, of which the following is a specification, reference being had to the accompanying drawings, forming part hereof.

In the drawings:

Fig. 1 is a front view of the collapsible, combined vanity-bench mirror and tray, showing my new design.

Fig. 2 is a side view of the collapsible, combined vanity-bench mirror and tray.

Fig. 3 is a side elevational view of the collapsible, combined vanity-bench mirror and tray, showing the device as it appears in a collapsed position.

Fig. 4 is a transverse sectional view taken along lines 4—4 of Fig. 1.

Fig. 5 is a plan view taken along lines 5—5 of Fig. 2.

I claim:

The ornamental design for a collapsible, combined vanity-bench mirror and tray, substantially as shown.

EVERETT O. RYDER.
